United States Patent Office

Des. 233,822
Patented Dec. 3, 1974

233,822

SWITCH PLATE

David P. Zagaroli, Hickory, N.C., assignor to Ajax
Hardware Corporation, City of Industry, Calif.

Filed Mar. 14, 1973, Ser. No. 341,022

Term of patent 14 years

Int. Cl. D13—99; D8—99
U.S. Cl. D8—181

Fig. 1.

Fig. 2.

Fig. 3.

Fig. 4.

Fig. 5.

Fig. 6.

Fig. 7.

FIG. 1 is a front view of the ornamental design of the switch plate;

FIG. 2 is a side view of the switch plate shown in FIG. 1;

FIG. 3 is a cross-sectional view taken along the line 3-3 of FIG. 1;

FIG. 4 is an end elevational view of the switch plate shown in FIG. 1;

FIG. 5 is a back view of the switch plate shown in FIG. 1;

FIG. 6 is a plan view of a modification of a design for a switch plate as illustrated in FIG. 1; and

FIG. 7 is a cross-sectional view taken along the line 7-7 of FIG. 6.

I claim:

The ornamental design for a switch plate, as shown and described.
